ACCOUNTING MACHINE

Fred M. Carroll, Yonkers, N. Y., assignor, by
mesne assignments, to International Business
Machines Corporation, New York, N. Y., a cor-
poration of New York

Application July 17, 1930, Serial No. 468,722

15 Claims. (Cl. 235—60)

The invention concerns an accounting machine and has for its principal object the provision of such a machine having an improved structure and operation and particularly one in which improved selective mechanism is provided for determining into which accumulators items shall be added.

This is a continuation in part of Serial No. 357,949, filed April 25, 1929.

10 Another object of the invention is to provide an accounting machine in which a large number of accumulators may be provided and in which any of the accumulators may be individually selected for item entry by an improved selecting mechanism.

15 Another object of the invention is to provide an accounting machine provided with accumulators which may be selected for receiving items of primary classifications and additional secondary accumulators which may be associated with any one or more of the primary accumulators to accumulate subtotals of items entered into the primary accumulators.

20 Another object of the invention is to provide a grand total accumulator in connection with an accounting machine according to the above objects into which items of all classifications may be entered.

25 Another object of the invention is to provide an accounting machine conforming to the above in which keys are provided to select the several accumulators and in which indicators may be provided to furnish a visual indication of the accumulators which have been selected to receive items.

30 Another object of the invention is to provide an accounting machine of the above type in which printing mechanism is provided to list items entered into the accumulators and in which provision is made for identifying the accumulator into which the entry is made on the printed list.

35 Another object of the invention is to provide an accounting machine of the above type in which new and improved total printing mechanism is provided.

40 Another object of the invention is to provide an accounting machine of the above type in which improved mechanism is provided to automatically print totals from all accumulators when a total taking operation is initiated.

45 Another object of the invention is to provide an accounting machine of the above type in which the accumulator selection is effected by means of electrically operated mechanism.

50 55 The advantages of the invention may be most

clearly visualized from a consideration of a particular machine embodying the several improvements although it will be understood that the invention is not intended to be limited to the particular mechanisms which are chosen for 60 illustration. The preferred embodiment consists of a plurality of accumulators disposed in a number of vertical rows, each vertical row containing a number of accumulators disposed one above the other. Each denominational order of 65 the several vertical rows is provided with a single operating member having a separate operating rack for each accumulator element in the particular vertical row. Each operating member may be controlled by keys of which there are 70 ten for each operating member. Depression of any key in a row effects differential movement of the operating member associated with that row and in consequence all the particular racks associated with the operating member are given a 75 differential movement corresponding to the depressed key. Certain selected accumulators only are meshed with the racks, however, so that the entry may be made at will into different accumulators.

80 The selection is effected by means of magnets of which one is provided for each accumulator and which on energization causes meshing of the accumulator wheels with the corresponding racks. These magnets may be controlled by accumulator selecting keys which are so arranged that when they are depressed singly or in combinations one magnet only will be energized for selecting the corresponding primary accumulator. The primary accumulating magnets in turn also control 85 circuits through which selection of one or more of a group of secondary or subtotal accumulators may be made. These circuits are arranged so that they may be plugged in such manner that any one or more subtotal accumulators may be 90 operated coincidently with any one or more of the primary accumulators. In addition a grand total accumulator is provided which is arranged to receive every item which is entered into any primary accumulator.

95 Printing mechanism may also be provided which is controlled by the amount entering keys to print a consecutive list of the items entered into the primary accumulators and additional printing mechanism may be provided controlled by the accumulator selecting keys to print an identifying number for the primary accumulator which receives each item. At the end of an accounting period totals may be taken and to this end total printing mechanism is provided consist- 100 105 110

ing of printing elements or wheels directly geared to the accumulator wheels so that their setting always agrees therewith. On initiation of total taking a travelling carriage is carried in turn past the total printing elements and an impression of the total standing thereon taken from each, the accumulators being returned to home position and the carriage restored to its starting position at the end of a total printing operation. The specific embodiment selected for illustration will now be described in detail in connection with the accompanying drawings in which:

Figs. 1 and 1a taken together show a left side elevation of the machine showing driving gears, paper feed unit, counter control magnets and side frame enclosing counters, listing unit and timer;

Fig. 2 is a right side elevation of the lower half of the machine showing keyboard, differential counter control, paper feed unit and drive of timer, counter control magnets and side frame enclosing counters. The upper portion of the machine is omitted as it is similar to Fig. 1;

Fig. 3 is a horizontal section on lines 3—3 of Fig. 2 showing a plan view of the listing device, driving gears, plug board, key board and paper feed unit;

Fig. 23 is a horizontal section on lines 23—23 of Fig. 22 showing a plan view of a counter and its actuating mechanism;

Fig. 24 is a front end elevation of a counter showing the type wheels and their latching device;

Fig. 25 is a plan view continuation of the right hand end of Fig. 23 showing the counter control magnet;

Fig. 26 is an elevational view taken on lines 26—26 of Fig. 2 showing the timing unit with the total printing contacts;

Fig. 27 is a vertical section on lines 27—27 of Fig. 26 showing the timing traveler and contact make and break means;

Fig. 28 is a vertical section on lines 28—28 of Fig. 26 showing the uni-direction clutch which does not drive the cams on the right hand end of the timing unit when the timing traveler returns to initial position;

Fig. 29 is a vertical section on lines 29—29 of Fig. 26 showing the contact make and break means;

Fig. 30 is a vertical section detail on lines 30—30 of Fig. 28 showing the construction of the timing clutch;

Fig. 31 is an enlarged left end elevation of the paper feed and printing carriage showing the gear train drive;

Fig. 31a is a section on line 31a—31a of Fig. 31;

Fig. 32 is a left hand end, front elevation of the paper feed and printing carriage;

Fig. 32a is a right hand end, front elevation of the paper feed and printing carriage showing the ribbon feed drive;

Fig. 33 is a right hand elevation of the paper feed and printing carriage;

Fig. 34 is a vertical section on lines 34—34 of Fig. 32 showing the paper feed and printing hammers cocking device;

Fig. 35 is a plan view, partly in section, of Fig. 32, showing the carriage driving gears, the printing hammers and type wheels of counters in dashed lines;

Fig. 36 is a vertical section on lines 36—36 of Fig. 32 showing the paper feed rolls, printing hammers cocking device and printing ribbon;

Fig. 37 is a vertical section on lines 37—37 of Fig. 32a showing mechanism for swinging the carriage against the counter type wheels for total printing;

Fig. 38 is an oblique detail section on lines 38—38 of Fig. 8 showing the reversing mechanism for controlling the ascent and descent of the printing carriage. The clutch is in position for ascent;

Fig. 39 is a skeleton view of Fig. 38, showing the directions of gear rotation and the position of the clutch for descent of the printing carriage;

Fig. 40 is a vertical section on lines 40—40 of Fig. 38 showing the traveler for actuating the impositively locked clutch shifting arm;

Fig. 41 is a detail view of the printed strip con-

taining individual totals and subtotals with respective counter numbers and the grand total;

Fig. 42 is a detail view of the printed listing strip containing individual items with their respective counter numbers;

Fig. 43 is the left hand half of the electrical wiring circuit showing the counter control magnets and total printing cams and contacts;

Fig. 43a is the right hand half of the electrical wiring circuit showing the counter selecting keys, listing solenoids, plug board and counter magnet contacts. Figs. 43 and 43a combined constitute the complete electrical wiring circuit.

The general arrangement of the machine is best shown in Figs. 1, 1a and 3 of which Figs. 1 and 1a taken together illustrate a vertical section through the machine and of which Fig. 3 shows the key board for entering items and selecting accumulators and the plug board for associating any desired sub-total or secondary accumulators with the primary accumulators. The present machine is provided with fifty accumulators of which thirty-nine act as primary accumulators for receiving items set up on the keys 50 of Fig. 3 and which are selected by the counter selecting keys 51 and 52. Ten of the accumulators are secondary or sub-total accumulators which are not selected by the keys 51 and 52 but by operation of selected primary accumulators. The plug board 53 at the left of Fig. 3 contains a group of sockets numbered 1 to 39 inclusive, which are connected to contacts associated with the primary accumulators. Groups of sockets designated A to K inclusive, are connected with selecting magnets for the sub-total accumulators. When the secondary sockets are plugged to the primary sockets an entry of an item into certain primary accumulators will result in entry of the same item into the associated secondary accumulators. For example, in the particular plugging illustrated in Fig. 3 secondary accumulator K is plugged to primary accumulators 9, 19, 29 and 39.

In this case any item selected for entry into primary accumulators 9, 19, 29 and 39 would also be entered into secondary accumulator K. In a similar manner certain other secondary accumulators are associated with other primary accumulators for entry of common items.

For convenience the accumulators designated generally at 55 are arranged in five vertical rows (see Fig. 3) each vertical row containing ten accumulators disposed one above the other (see Figs. 1 and 1a). An item to be entered is first set up on the amount keys 50, this item or the setting of the keys being indicated by the visual indicator 56 prior to entry into the selected accumulator. Thereafter certain of the counter selecting keys 51 and 52 may be depressed to select the desired accumulator to receive the entry. For example, if a particular entry were to be entered into the accumulator 31, key 52 marked "3" and the key 51 marked "1" would be depressed. Until this selection is made operation of the machine is prevented. Depression of the operating key 57 causes the machine to operate after the item has been set up and the accumulator selected, causing entry of the item into the selected primary accumulator as well as into any sub-total accumulators which have been plugged on the plug board 53 to the particular primary accumulator selected. Incidentally the same item is entered without further selection into the grand total accumulator. An item may be repeated without additional set up

through a repeat lever mechanism 60. After a plurality of items have been entered total printing may be effected by shifting a total print lever 61a and thereafter depressing the operating key 57.

The reports printed by the machine are illustrated in Figs. 41 and 42 of which 41 shows a total sheet and 42 shows a listing sheet. In Fig. 42 the column of figures to the left designates the primary accumulators which receive the items represented by the figures to the right. This is simply a list of the items which have been entered identifying the particular accumulators into which the several entries are made. For example the first item 3,256,042 was entered into accumulator 31; the second item was entered into accumulator 6 and so on. This list is made concurrently with item entry. The total sheet shown in Fig. 41 is printed on operation of the total mechanism 61 in Fig. 3. When a total is initiated a complete report such as illustrated in Fig. 41 is printed. That is, the totals for the thirty-nine primary accumulators are shown designated by the figures 1 to 39 inclusive, the totals of the sub-total accumulators designated by A to K and the grand total accumulator by GT. It will be noted that the conformation of the totals on the total sheet corresponds to the arrangement of the accumulators. That is, the totals occur in five vertical rows, each row containing the totals of ten accumulators. In machine operation the upper horizontal row including the totals of accumulators 30, 20, 10 GT and A are printed simultaneously. Thereafter the next horizontal row including accumulators 31, 21, 11, 1 and B are printed and so on.

Driving system

The general drive of the machine is illustrated most clearly in Figs. 1a, 2, 4, 5, 8, 13 and 14. The source of power in the present case is illustrated as a motor driven pulley 64 which through suitable gearing constantly operates a shaft 65 for driving the several listing and adding mechanisms and a shaft 66 for driving the several total taking mechanisms (see Fig. 1a). The operating key 57 (see Figs. 2 and 3) controls contacts through linkage indicated generally at 67 closing these contacts when depressed, and, as will be hereinafter explained, if an accumulator has been selected when this key is depressed the magnet 68 (Figs. 4 and 14), hereinafter referred to as the listing magnet, will be energized. This magnet upon energization attracts its armature 69 fixed on a rocking lever 70 and by rocking the latter releases a pawl 71 pivoted on a block fixed to shaft 72, hereinafter referred to as the listing shaft, permitting this pawl to engage a notch in disk 73 carried by shaft 65. This is the usual one revolution clutch mechanism and it will be understood that when the magnet is energized the listing shaft 72 will make one revolution and then stop, the pawl 71 being cammed out by member 70.

A similar one revolution clutch is provided in connection with the total shaft 74. The machine is set up for total taking by shifting total lever 61a (see Fig. 13) to the right, rocking a shaft 75 on which it is fixed and raising link 76 pivoted to an arm 77 on the shaft 75. Link 76 is connected at its lower end to an arm 78 on shaft 79 whereupon operation of the total lever causes the shaft 79 to rock clockwise.

A second arm 80 fixed to shaft 79 is pivotally connected to a link 81 (see also Fig. 14) connected

80

85

90

95

145

150

to a link 82 having its other end connected to an arm 83 on the rock lever 70 which carries the armature 69 of listing magnet 68. When the total key 61a is operated, then, the upper end of link 82 is forced into the path of the end of a pivoted lever 85 which serves the same purpose for the totaling clutch as lever 70 does for the listing clutch. When the link 82 is so moved and the magnet 68 thereafter energized, rocking member 85 as well as rocking member 70 will be operated causing engagement of the listing clutch as well as engagement of the totaling clutch which is similar in form to the listing clutch. It will be noted from Fig. 13 that when the total lever 61a is thus operated it is latched by latching lever 61b and held in operated position until released either by moving the latch 61b to the left or by energization of the trip magnet 91 which through linkage 92 rotates the latch lever 61b about its pivot and releases total lever 61a. As will hereinafter be explained the trip magnet 91 is controlled from the total taking mechanism and will be energized to release the total lever only after the total taking operation is completed thus providing for a plurality of successive machine cycles during which the listing shaft 72 as well as the total shaft 74 rotates.

The list shaft 72 (see Fig. 13) is geared direct to the main cam shaft 94 of the machine and through other gearing to additional shafts which are to rotate when the machine is performing either listing or totaling operations. The total shaft 74 drives shaft 95 which through supplemental gear trains shown generally in Fig. 5 operates the several shafts which are necessary for total taking operations.

Generally those shafts which are geared to the listing shaft operate in every machine cycle, listing as well as total printing, while those shafts geared to the total shaft operate only during total printing operations.

Accumulating

The accumulating operation may be best understood from Figs. 7, 19 and 22. Referring to Fig. 19 the amount keys 50 are held in upper position by springs 100. On depression of any key in a row, to select a particular digit for entry, the locking bar 101 is shifted to the left by bell cranks 102, one arm of each of which is pivoted to the bar 101 and the other arm of which coacts with pins 103 on the shanks of keys 50. When this bar is so moved it is latched in its left hand position by a spring pressed latch 104 and pins 105 on the bar encounter notches in the key shanks to hold the depressed key down and to lock the other keys in their upper position. Any set up may be erased before entry by an erasing key 108 whose shank carries a pin 109 cooperating with latch 104 to release the same and permit the bar 101 to return to normal position under action of a spring when the erasing key is depressed. The movement of locking bar 101 to the left rocks a small bell crank 110 which cooperates with the tail of a zero latch 111 and rocks the latch clockwise about its pivot 112. This release of the zero latch is necessary to permit movement of the differential mechanism. When the total lever is shifted, shaft 75 is rocked clockwise and a member 192 fixed thereto and extending into a notch in bar 101 locks the bar in inoperative position and prevents manipulation of the keys. Incidentally while bar 101 is shifted to the left in response to key operation the total lever is locked as shaft 75 cannot turn.

Referring now to Figs. 7 and 19 shaft 94, which, it will be recalled, is driven directly from the listing shaft, carries a box cam 116 having a groove into which extends a roller on lever 117 the lever being pivoted at 118. When shaft 94 rotates, the lever 117 moves first clockwise and then counterclockwise about its pivot 118. A link 120 is connected at the lower end of lever 117 and moves first to the left and then to the right. This lever is pivoted to an arm 121 fixed to rock shaft 122, rocking the latter. For each row of keys a member 123 is provided on the rock shaft 122. Freely mounted on the shaft 122 for each bank of keys is a differential stop member 124 and also a member 125 attached to the member 124 by a compression spring 126. The member 125 carries a pawl 127 having a cam arm 128 attached thereto cooperating with a cam 129 on member 124. The spring 126 normally tends to force the member 125 counterclockwise with respect to the member 124 permitting the pawl 127 to drop into a notch in member 123 as shown in Fig. 19 where it is held by the co-operation of the cam member 129 with the cam arm 128. As the shaft 122 with member 123 rocks clockwise it will carry the members 124 and 125 along with it owing to the locking action of the pawl 127 with the member 123. The member 124 will thus move with the member 123 until member 124 meets an obstruction. Member 124 at its upper end carries a spring pressed dog 130 which travels in the path of the key shanks when the keys are depressed. When this dog meets a depressed key shank the movement of member 124 is stopped, that of 125 continuing causing compression of the spring 126 whereupon the cam arm 128 moves along the cam member 129 permitting pawl 127 to be cammed out of the notch in member 123 owing to the angular relationship between the trailing edge of the notch and the angular surface of pawl 127.

Pawl 127 thereupon moves to the position shown in Fig. 7, with its nose 135 entering a notch in a sector plate 136, and is locked there by the concentric surface 137 of the member 123. It will be understood, then, that the member 125 is moved to a position corresponding to the depressed key and thereafter stopped and locked in this position.

The members 124 and 125 are guided in their movement by a roll 138 coacting with the outer surface of sector 136. Member 125 is provided with an arm 140 to which is pivoted a link 141 whose upper end is pivoted to a bell crank 142. The bell crank 142 through linkage 143 rocks a shaft 152 through arms fixed thereto, and raises operating bars 145 for operating all the accumulator racks of the denominational order corresponding to the particular row of keys. One of the mechanisms just described is provided for each denominational order or bank of keys.

The connections between the operating bars 145 and the accumulator racks are clear from Fig. 22. Each accumulator rack consists of two sections 131 and 146 mounted side by side and held together by a pin and slot connection. Section 131 is connected at one end to a lever 148 which is pivoted at 150 and pivotally connected at 149 to bar 145 so that when the bar rises member 131 is displaced to the left. The rack section 146 is slidably connected to section 131 by pins 147, one on each section engaging a slot in the other section. A spring 701 normally holds pin 147 on section 131 against the end of the slot in rack section 146 so that the two sections move

as a unit when operating bar 145 moves. Rising of the bar 145 causes lever 148 to rock counterclockwise about its pivot and forces rack 146 from its home position represented by the upper rack 5 in Fig. 22 to a position corresponding to the depressed key as illustrated by the lower rack in Fig. 22.

All the wheels 155 for each separate accumulator are mounted in a frame 158 pivoted at 159 10 which has an extending arm 160 slotted to receive a bar 161 carried by a frame 162 pivoted at 150 and having a rear extension 164 cooperating through a pin and slot connection with a lever 165. The lever 165 is controlled by the 15 counter selecting magnet 175 (see Fig. 1). On energization of the magnet 175 it attracts its armature and the lever 165 rocks downwardly, rocking the rear arm 164 of frame 162 downwardly and the forward end of this frame upwardly, carrying the rod 161 together with the 20 rear extension 160 of frame 158 upwardly whereupon the frame 158 which carries the accumulator wheels 155, on rotating counterclockwise about its pivot places the accumulator wheels in 25 mesh with their racks 146 and incidentally rocks the frame 156. The magnets 175 as will be hereinafter explained are controlled from the counter selecting keys 51 and 52. Thus, when any magnet is energized, its corresponding accumulator 30 will be placed in mesh with its racks, the racks are thereafter moved differentially to the extent determined by a depressed amount key and the amount is rolled into the accumulator. After the rack has finished its forward movement 35 the selecting magnet 175 is deenergized and a spring 176 restores the several accumulator operating parts to home position moving the accumulator wheels 155 out of cooperation with their racks and allowing the item to be retained 40 on the accumulator wheels. After this (see Fig. 7) the continued rotation of the box cam 116 to home position restores the differential mechanism and a projection 180 on member 123 in its return movement encounters the end of pawl 45 127, cams the latter about its pivot, restores the pawl to its normally latched position in the notch in member 123 and carries it to home position.

If no key is depressed in a particular row, the zero latch 111 remains in the position shown in 50 Fig. 19 and prevents movement of the member 124, the pawl 127 being released and locked in the zero notch of sector 136 in the same manner as just explained for a depressed key. During 55 the cycle shaft 183 (see Figs. 19 and 13) through linkage 185 operated by a cam 186 carried by listing shaft 72 oscillates first clockwise and then counterclockwise. In its clockwise movement a dog 188 carried by an arm 189 fixed to shaft 183 snaps under the tail piece 190 of latch 104 (Fig. 59). On the counterclockwise movement of the 60 shaft 183 which occurs toward the end of the cycle the dog 188 cooperating with the tail piece 190 rocks the latch 104 out of latching position and permits locking bar 101 to move to the right thus releasing the depressed key.

If desired, the same entry may be repeated without resetting of the keys by operating the repeat mechanism 60 (see Fig. 13). When the repeat lever 60a is moved to the left it rocks shaft 197 counterclockwise and the lever is latched in 65 operated position by a latch member 60b. Rocking of shaft 197 (see also Fig. 19) moves a cam member 198 carried thereby into the path of tripping dog 188 and prevents release of the latch 104 by this dog at the end of a cycle. Thus

the locking bar remains to the left holding the original key depressed. The item may be repeated as many times as desired and the repeat mechanism may be released thereafter (see Fig. 13) by pressing downwardly on the head of latch 60b, releasing repeat lever 60a whereupon spring 199 returns it to its normal inoperative position.

Transfer

As usual in accumulating machines transfer mechanism is provided to transfer one unit to the next higher denominational order whenever an accumulator wheel passes through zero on receiving an entry. Referring to Fig. 22 a transfer rack is shown at 201 provided with two teeth and suitably guided at one end by a pin 202 and at the other end by a plate 203. In its normal demeshed position the accumulator wheel 155 meshes with the teeth of the transfer rack as indicated for the upper accumulator in Fig. 22 and during actual entering operations the wheel is demeshed therefrom as indicated for the lower accumulator in this figure. Pivoted to the frame 158 is a spring pressed transfer hook 204 whose hook portion lies in the path of a projection 205 carried by a disk integral with the counter wheel 155. When the counter wheel passes through the zero the projection 205, having its forward end sloped, encounters the end of the transfer hook and rocks it clockwise about its pivot. A transfer latch 206 is pivoted at 207 and connected at 208 to one end of the transfer rack. The lower end of this latch 206 normally abuts the rear end of the transfer hook 204 and holds the associated transfer rack in its forward position as shown for the upper accumulator in Fig. 22. It will be understood that each hook 204 controls the rack 201 of the next higher adjacent accumulator wheel so that the proper transferring operations may occur.

Also pivoted to the rear end of the transfer rack 201 is a bar 209 carrying a pivoted hook 210 at its rear end. The member 209 is normally held in its upper position by a spring 213. When the accumulator is demeshed from its operating rack 146 a pin 214 on frame 158 pulls down the hook 210 to lower the member 209 as shown for the upper accumulator in Fig. 22.

When the counter wheel meshes with its rack the pin 214 rises permitting spring 213 to raise member 209 as shown for the lower accumulator in this figure. A shaft 216 is provided for each horizontal row of accumulators which shaft carries a curved member 217 coacting with the rear edge of members 209. These shafts 216 (see Fig. 125 2) extend to the outside of the machine casing and each carries an arm 218 pivoted to a vertical bar 219. The bar is pivoted at its lower end to an arm 220 fast to shaft 224. This shaft (see also Fig. 8) extends to the interior of the machine and has 130 fixed thereto a spring pressed arm 225 carrying a roller 226 cooperating with a cam 227 on shaft 228. Shaft 228 (see also Fig. 13) is driven from the listing shaft 72 of the machine and rotates whenever the machine is operating. Each cycle 135 the cam 227 rocks arm 225 and consequently shaft 224 clockwise lowering bar 219 and rocking the shafts 216. The curved member 217 thereupon encounters the rear edge of member 209 of any accumulator which is in engagement with its 140 rack during that cycle and moves the transfer rack to the left as shown in Fig. 22. The transfer rack is held in this position by the member 217 until accumulating operations are finished. If any wheel 155 passes through zero, rocking its transfer 145 150

hook 204, the latter slips off the first step of the member 206 to the position shown for the lower accumulator in Fig. 22, rearward movement of the transfer rack 201 being prevented at this time by the curved member 217. As the accumulator wheels are demeshed from the operating racks 146 and just as they encounter the teeth of the transfer rack 201, pin 214, owing to the rocking of frame 158, is lowered, pulls down on the hook 210 and lowers member 209 out of the path of curved member 217 whereupon spring 228 operating upon latch 206 causes the transfer rack 201 to move to the right thus entering the transferred unit into the accumulator wheel.

15 The rack stays in this shifted position until the next cycle in which the particular accumulator is active. If the accumulator remains inactive during the following machine cycle, the member 209 will be held depressed by the pin 214 and the curved member 217 does not encounter member 209 to restore the transfer rack. During the next cycle in which the accumulator is active just after the wheel 155 engages its operating rack 146 member 217 encounters member 209 restoring the rack 201 to the left and relatching transfer hook 204 on the first step of transfer latch 206 as shown in the upper accumulator in Fig. 22.

Circuit operation for accumulation

30 The motor M which drives the machine is started into operation as soon as the switch SW is closed (Figs. 43 and 43a). After a number has been set up on the keyboard and an accumulator has been selected, thereby closing contacts 289 and 290, as will be explained later, a circuit for the listing clutch magnet 68 may be established by depressing start key 57. This circuit is as follows: from source S through wire 614, start key contacts 57, locking contacts 289 or 290, clutch magnet 68 and common return 254 back to the source S. This circuit persists only as long as the start key is held depressed but instantaneous energization of the magnet 68 is sufficient to cause the one revolution listing clutch to engage for a complete revolution as is well understood.

Primary accumulator selection

It will be recalled from the explanation under "Accumulating" that the several primary accumulators may be selected by energizing their associated magnets 175, (see Fig. 1) which magnets are controlled by the counter selecting keys 51 and 52 shown in Fig. 3. Referring to the circuit diagram in Figs. 43 and 43a, it will be noted that the units keys 51 each control a series of contacts designated by the letter C followed by a numeral while the tens keys 52 control two pairs of contacts 231 and 232. The operation of any units key 51 furthermore opens a common pair of normally closed contacts 235. The operation of any tens key 52 opens a pair of common contacts 236 and closes a pair of common contacts 237. In Fig. 43 the primary accumulator selecting magnets 175 are shown in four vertical rows as their accumulators are located on the machine. The row to the left contains magnets for accumulators 30 to 39 inclusive; the next row magnets for accumulators 20 to 29 inclusive; the next row contains magnets for accumulators 10 to 19 inclusive; and the fourth row contains magnets 175 for primary accumulators 1 to 9 inclusive as well as the grand total accumulator magnet 175G. The circuits connecting the magnets 175 to the units keys 51 and the tens keys 52 are such that only one magnet 76 will be energized on depressing either a tens key,

a units key or one tens key and one units key. The magnets 175 for selecting accumulators 30 to 39 are connected through a common wire 238 to contact 231 of the third tens key. In like manner the magnets 175 for accumulators 20 to 29 are connected by common wire 239 to similar contacts of the second tens keys and magnets 175 for accumulators 10 to 19 are similarly connected to contacts 231 of the first tens key.

The magnets 175 in the upper horizontal row for accumulators 10, 20 and 30 are connected through wire 243 to common contacts 235 opened by operation of any of the units selecting keys. The magnets 175 in each horizontal row below the uppermost one are connected through the appropriate contacts C of the units keys 51 to one side of the source of energy S. For example, those in the fourth row from the top, comprising magnets for accumulators 3, 13, 23 and 33 are connected through contacts C3, C13, C23 and C33, respectively, and wires 263, 246 to cam contacts L-1, closed during listing and thence through wire 614 to one side of the source S. The other horizontal rows are connected in like manner to be controlled by the appropriate units keys.

It will be noted that if a tens key 52 alone is depressed one of the magnets 175 will be energized in the upper row, that is a magnet corresponding to accumulators 10, 20 or 30. The selecting circuit in this case extends from source of energy S to cam contacts L-1, closed during the entering portion of each cycle, thence through wire 246 to contacts 237 closed by operation of any of the tens keys, thence through wire 248 and contacts 235, closed as long as none of the units keys are operated, through wire 243 which is common to one side of the magnets 175 for the 10, 20 and 30 accumulators. The 10, 20 and 30 accumulators are each connected individually through wires 240, 239 and 238 to contacts 231 of the tens keys. The magnet which is selected depends on which key is operated and the circuit is continued from contacts 231, through wires 253 and common return 254, to the other side of the source of energy S.

If a units key 51 alone is depressed, the magnets for accumulators 10, 20 and 30 cannot be energized as their circuit is opened at contacts 235. In this case one of the magnets 175 for accumulators from 1 to 9 respectively, will be selected. These magnets are connected through common wire 255 to contacts 236 controlled by any of the tens keys. As long as the tens keys are not operated these contacts remain closed and connect one terminal of the units magnets through the common return wires 253 and 254 to one side of the source of energy. The other terminal of the units magnets are connected individually through contacts C1, C2, C3 etc. to wires 261 to 269 inclusive. The latter wires are in turn connected to wire 246 and through cam contacts L1 to the other side of the source of energy. The operation of any tens key 52 by opening contacts 236 prevents the selection of any of the magnets 175 for the accumulators 1 to 9.

If both a units key 51 and a tens key 52 are operated, magnet 175 which is selected will depend on the particular keys which are depressed. For example, if the 2 key 52 is depressed and the 6 key 51 is depressed magnet 175 for accumulator 26 will be selected. The circuit in this case extends from source of energy S through contacts L-1, through wires 246 and 266 to contacts C-26 controlled by the sixth units key to magnet 175 for accumulator 26, through common

wire 239, to contacts 231 of the second tens key 52, thence through wire 253 and common return 254 to the other side of the source S. It will readily be seen that the other magnets corresponding to different combinations of keys will be selected in a similar manner.

The grand total accumulator GT is selected for operation on each accumulating operation of the machine so that all items entered into the 10 machine will be totalized on this accumulator. The selecting magnet 175G for this accumulator is controlled by cam contacts L-2 controlled from the listing shaft and closed on all operating 15 cycles of the machine. The circuit for this magnet extends from source S through wire 614 to contacts 605, controlled by the total shift lever and closed whenever this lever is out of totaling 20 position, thence through cam contacts L-2 and grand total magnet 175G back to source S through common return 254.

The operation of the counter selecting keys 51 and 52 is shown in Figs. 9 to 11. In Fig. 9 the units keys are shown but it will be understood that the tens keys are entirely similar except 25 that there are only three of them instead of nine. The keys 51 are guided by suitable slots in the machine frame and suitable slots in their shanks cooperating with pins 275 supported on the machine frame. The keys are spring pressed upwardly by springs 276 cooperating with pins 275 and shoulders on the key shanks. Each key when depressed operates a bell crank 277 through a pin 278 on its shank and forces a locking bar 279 to the left whereupon it is hooked in the left 30 hand position locking the depressed key down and the other keys up in a manner entirely similar to that explained in the case of the amount keys. The latch 282 which holds the locking bar 279 to the left is entirely similar in function 35 to the latch 104 (see Fig. 19) for holding the locking bar 101 of the amount keys. This latch is released at the end of a cycle by dog 283 carried by a member 284 on shaft 183 which operates the release mechanism for the amount keys 40 as previously explained.

The locking bar 279 when it moves to the left operates a bell crank 285 which rocks a lever 286 pivoted at 287 and raises a link 288 operating bell cranks designated generally at 288' for operating the several contacts 235, 236 and 237 whose purpose has been previously explained. Additional contacts 289 and 290 are closed on the operation of the locking bars to the left. Contacts 289 are individual to the units bar and contacts 290 are individual to the tens bar. The purpose of these contacts is to prevent machine operation until accumulator selection is effected as previously explained. Each key 51 and 52 carries a contact 291 at its lower end to cooperate with contacts 292 carried by, but insulated from, a block 293. This block is supported by a pair of bell cranks 294 and 295 connected to each other by a link 296 and operated by an arm 297 pivotally connected to link 298. Link 298 is pivoted to and operated by a spring actuated arm 299 fixed to shaft 300. Also fixed to shaft 300 is an arm 303 carrying a roller 304 cooperating with a cam 305 fixed to the list shaft 72. During each 20 cycle, as the list shaft rotates, the cam actuates the arm 299 to raise block 293, bringing contacts 291 on the key shanks which have been depressed thus completing the circuit for selecting the accumulator magnets and holding it complete until

the end of the entering cycle when the block is lowered to break it.

The contacts 292 are formed of opposing clips 309 and 310 (see Fig. 11) which are attached to the block 293 in a manner which will be clear from Fig. 10. The units keys each close a plurality of circuits, as a number of contacts 310 are bridged to contacts 309 by the contacts 291 carried by the key shanks. These contacts comprise the groups on the circuit diagram designated by the letter C followed by a numeral. Each tens key controls only a single pair of contacts. At the end of the entering cycle the latch 282 is released by dog 283 in the same manner as previously explained for the amount keys and the locking bar 279 moves to the right from the action of spring 311. An interlock comprising stop 312 on shaft 75 is provided as in the case of the amount key locking bars.

90

95

Indicators

In Fig. 3 indicators are shown at 56 for indicating the amounts set up on the amount keys 50 and similar indicators are shown at 58 for indicating the particular accumulator which is selected by the keys 51 and 52. The operation of the indicators may be understood from Figs. 5 and 19. In Fig. 5 the indicators 56 and 58 are frictionally driven from a shaft 315 connected by gears 316, shaft 317 and gear train 318 to the 105 pulley 64. As long as the motor is in operation these indicators tend to turn. Referring to Fig. 19, each indicator 56 is provided with a group of spirally arranged pins 316 one pin being provided for each key in the associated row. A lever 321 110 pivoted at 322 has an overturned lip at 319 which normally coacts with the proper pin 316 to hold the particular indicator wheel 56 in zero position. The lever 321 is pivoted at its lower end to a bar 320 constantly pulled to the right by spring 320' thus tending to urge the lever 317 into position to hold the indicator 56 at zero.

100

105

110

115

The bar 320 is pivotally connected to a series of plates 323, one of which is provided for each key, one end of the plate being pivoted at 324 to 120 the machine frame and the other end being pivoted to the bar 320. The plates 323 are provided with triangular openings at 326 into which projects a pin 327 carried on the shank of keys 50. The sides of the openings with which the pins 327 125 coat are progressively steeper from the #1 to the #9 key. When the #9 key is depressed the bar 320 is cammed to the right sufficiently to rock lever 317 so that its lip 319 releases the zero pin 316, encounters the next spirally arranged pin 130 and stops the indicator wheel in nine position. Depression of the other keys progressively displace the bar 320 in like manner causing the member 317 to rock sufficiently to engage pin 316 corresponding to the key depressed. When the depressed key is released at the end of the cycle spring 320' returns bar 320 to the right causing member 321 to again move into position to engage the zero pin 316 whereupon the indicator is returned to zero.

135

140

145

Indicators 58 for indicating the accumulators selected operate in an entirely similar manner and the mechanism for operating them has not been illustrated in detail. By referring to Fig. 8 it will be noted that the operation is substantially the same as that just described for the amount key indicators.

Secondary accumulator selection

The secondary accumulators A to K are not 150

selected directly from the keys 51 and 52 but from the primary accumulators so that any item entered into a primary accumulator may also be entered into a preselected secondary accumulator or accumulators. The secondary accumulator selecting magnets are shown in Fig. 43 in the vertical row to the right and are designated 175S. Each of these magnets is connected from the source S through common wire 614 and contacts 607, controlled by the total shift lever through wire 621 to one terminal of magnets 175S. The other terminal of each magnet 175S is connected individually through wires 622 to a group of plug sockets 623.

15 Each primary accumulator (Figs. 1 and 1a) controls a pair of contacts 625 which are normally open due to their own resiliency. When the primary selecting magnet is energized to attract its armature and rock arm 165 to engage the accumulator wheels with their operating racks, an extension 626 on the armature forces a rod 627 to the left and rocks a lever 628 to close the corresponding contacts 625. The latter contacts therefore close when the primary accumulator becomes operative and remain closed as long as the primary accumulator is in operation.

16 The contacts 625 (see Fig. 43a) are all connected to the source S through cam contacts L—3 which are operated from the listing mechanism and are closed during the listing accumulating operation and open just prior to deenergization of magnets 175 to remove sparking from contacts 625. Each pair of contacts 625 is also connected to an individual socket 631 through which it may be plugged to any one of sockets 623 connected to the secondary accumulator selecting magnets 175S. It will therefore be understood that any secondary accumulator can be controlled from any primary accumulator to receive the same items from the keyboard.

Listing

17 The machine prints each item as it is entered into the accumulator, together with the number of the primary accumulator into which the entry is made. The listing mechanism may be understood from Figs. 14 to 18. In Fig. 15 the shafts 152 which as previously explained are rocked by the differential mechanism to an extent determined by the depressed amount keys, are provided with arms 340 to which are pivoted links 341 whose upper ends are pivoted at 342 to extending arms of type sectors 343 carrying the amount type 344. Each type sector 343 is provided with a notch at 345' which slips over a rod 345 and the type sector is pressed against the rod 345 by a bell crank 346 urged counterclockwise by a spring 347 and provided with a link 348 bifurcated at its end to engage a pin on the type sector 343 and hold it in place against the rod 345 but permitting it to be yeldingly displaced to the right from said rod. It will be understood that as the shafts 152 rock under control of the differential mechanism the type sectors move until the proper type is in printing position opposite the platen 350. At a certain point in the cycle the selected type are forced against the platen by a hammer 351, the hammer engaging suitable aligning notches 352 in the type sector 343 the spring 347 yielding to permit this operation. The hammer is operated by a spring 353 and is normally latched by a latch 354 mounted on an arm 355 fixed to shaft 356. This shaft 356 (see also Fig. 14) is rocked first counterclockwise to tension spring 353 and then clockwise

during each cycle. The rocking is effected by arm 357 fixed to shaft 356 and connected through link 358 to lever 359, one of whose arms carries a roller 360 cooperating with a cam 361 fixed to the main cam shaft 94 of the machine.

18 A trip latch 365 (Fig. 15) has a hooked end 366 cooperating with an extension 367 on latch 354. This trip latch is pivoted at 368 and is provided with a pin 372 which projects into an L-shaped groove 369 in a member 373. Normally the pin 372 rests in the horizontal portion of the groove 369 and holds the trip latch 365 elevated out of the path of extension 367 on hammer latch 354. The member 373 is pivotally connected at its lower end to a lever 374 pivoted at 375 and having its end 376 cam shaped to coat with the lower surface of type sector 343. When the type sector 343 leaves zero position, its lower surface coating with the cam extension 376 permits lever 374 to rock counterclockwise under influence of a spring 378. This lowers link 373 and consequently pin 372 thereby also lowering the trip latch 365 so that its hooked end 366 extends into the path of hammer trip pawl 367. During the clockwise movement of shaft 356 extension 367 encounters hooked end 366, rocks the pawl 354 out of engagement with the hammer 351 and permits the latter through action of spring 353 to engage the type sector 343 and force it to the right to effect printing.

19 At the end of the printing cycle the hammer is restored by a bail 380 fixed to shaft 381 (see also Fig. 14). The shaft 381 has an arm 382 connected by a link 383 with a three-armed lever 384 loosely pivoted on shaft 385. One arm of the lever 384 carries a roller 386 cooperating with a cam 387 mounted on the main cam shaft 94 to rock the lever and consequently the shaft 381 forcing the hammer restorer 380 (see Fig. 15) against an extension on the hammer to return it to normal position.

20 At this time also the hammer trip latch 365 is restored to its normal upper position by bail 390 fixed to shaft 391 which through linkage 392 (see Fig. 14) is also operated from the three-armed lever 384. At the end of a cycle when the trip latch is restored the hammer pawl reengages the hammer 351.

21 The printing sectors for the two positions to the extreme right, which normally represent cents, do not depend upon a hammer trip latch to release their hammer pawls 354 as it is always desired to print in these two places even though the representation be zeros. The hammer pawls 354 for these positions (see Fig. 16) are tripped by an extension 394 on comb plate 395 which serves as a guide for the printing sectors 343. The extensions 367 encounter this projection 394 and the hammer pawls 354 for the cents positions are always tripped. In the remaining positions it is not desired to print zeros unless they occur to the right of a significant figure and therefore as usual the presence of the figure to the left effects zero printing in columns to the right where no significant figure is selected from the keys. Referring to Fig. 15 it will be noted that if any type sector 343 does not leave zero position the latch 365 will not be lowered and therefore its hammer 351 would not be tripped. Each member 373 is provided with a sidewise extension at 398 which extends over a projection 399 on the next adjacent hammer trip latch 365 to the left. When any hammer trip latch 365 is lowered its projection 399 encountering the extension 398 of the adjacent member 373 rocks

this member slightly counterclockwise bringing the vertical portion of slot 369 under the pin 372 carried by the adjacent hammer trip latch 366. This adjacent hammer trip latch thereupon is lowered into the path of extension 367 and effects printing of a zero to the right.

The number of the selected primary accumulator is printed opposite each item. The sectors for printing the accumulator numbers are electrically controlled. Referring to the circuit diagram in Figs. 43 and 43a a magnet 405 is provided for each unit key 51 and a magnet 406 is provided for each tens key 52. In addition a zero magnet 407 is provided in the units order.

When any units key 51 is depressed its corresponding magnet 405 will be energized. The circuit for a particular key, for example the sixth units key, may be traced as follows: from the source of energy S, cam contacts L—1, wire 246 to contacts CO6 for the sixth units key to magnet 405 for the sixth digit, thence through common wire 409 and resistance 410, through contacts 236 which remain closed as long as a ten selecting key 52 is not depressed and to the wire 253 and common return 254 to the other side of the source S. If a tens key 52 alone is depressed, for example the second tens key, denoting that accumulator #20 has been selected, the indicating magnet selecting circuit extends as follows: from source S, contact L—1, wire 246 through contacts 237, closed when a tens key is depressed, and wire 248 to contacts 235, closed as long as no units key is depressed, thence through the zero magnet 407, wire 409 and the second magnet 406 thence to the lower contacts 232 of #2 tens key 52 and through wires 253 and common return 254 to the other side of the source S.

Depression of a tens selecting key and a units selecting key selects the appropriate solenoids 405 and 406 to indicate the composite number represented by the two. Depression of the units key in this case opens contacts 235 and cuts the zero solenoid 407 out of circuit. Thus the circuit extends through the proper tens solenoid 406 and the units solenoid 405 in series, the circuit being completed through contacts 232 of the depressed tens key and the contacts CO of the depressed units key.

The units solenoids 405 and 407 are arranged in arcuate configuration on a bracket 411 (Fig. 14) formed on the machine frame and the tens solenoids 406 are similarly arranged on a bracket 412 (Fig. 15). Each solenoid is provided with a core 413 (Fig. 17) to which is pivoted a lever 414 having a spring 415 to normally retract the core 413. When any solenoid is energized to attract its core the lever 414 is rocked about its pivot forcing its upper end into the path of an extension 416 on type sectors 417 which carry the indicating type for the accumulators. Referring to Fig. 15 the tens type sector 417 is illustrated. This sector also is provided with a notch 418 which fits over rod 345. Loosely mounted on rod 345 is a bell crank 421 carrying a bracket 422 on one arm to which a spring 423 is attached. The spring is also attached to the type sector 417 and serves to seat the sector properly on the rod 345. The other arm of bell crank 421 is pivoted to an upward extension 424 of arm 425 fixed to shaft 385. The shaft 385 (see Fig. 14) has an arm 326 fixed thereto provided with a roller 327 cooperating with a cam slot in cam 361 on main cam shaft 94. As the latter shaft rotates the shaft 385 is rocked clockwise, lowering

arm 425 and rocking bell crank 421 (Fig. 15) clockwise.

Through the action of spring 423 the type sector 417 is also rocked clockwise until its downward projection 416 encounters the end of a lever 414 which has been operated by a solenoid. When this occurs the type sector stops, the spring 423 now stretching to permit bell crank 421 to move to the limit of its movement. The type sectors 417 are thus positioned with the type corresponding to the energized solenoids 405, 406 and 407 opposite the platen 350.

At the usual printing time the hammers 351 cooperating with the sectors 417 are operated in a manner entirely similar to that just explained for the hammers cooperating with the cents amount keys. That is, the hammer pawls 354 for these hammers are tripped every cycle by an extension 431 on guide plate 395 (see Fig. 16). The selected accumulator numbers are thus printed each listing cycle.

Listing paper feed

The platen 350 (Fig. 15) is moved once each listing cycle to space the listing slip paper. This is done by a ratchet wheel 435 fixed to the platen (Fig. 14) having an operating pawl 436 mounted on a member 437 pivoted on the platen shaft. The member 437 is oscillated once each cycle by a link 438 connected to the three arm lever 384. The pawl 436 is yieldingly held against the ratchet wheel by a spring 441. The printing ribbon 442 is also spaced after each printing operation by the platen (see Fig. 16). A bevel gear 443 is fixed to the platen on its end opposite the ratchet 435 and meshes with a bevel gear 444 which operates ribbon feed roll 445 through gears 446.

Total printing

The total printing wheels 450 (see Figs. 22, 23 and 24) are each provided with an attached gear 451 and are freely mounted on rod 157. Also mounted on this rod is a frame 156 carrying intermediate gears 460 gearing each total printing wheel directly to its counter wheel 155. The side arms of frame 156 are bifurcated and fit over the axis 168 of the counter wheels so that the frame rocks when the counter wheels are lowered into engagement with their racks. The total printing wheels thus have a fixed axis and are always set according to the amount on the counter wheels. Each accumulator is provided with a locking plate 452 having an extension 454 for each gear wheel 451.

The locking plate is normally urged downwardly by spring 453 forcing the extensions 454 between the teeth of gears 451 to lock the total printing wheels in adjusted position. Prior to each operation of the accumulator the locking plate 452 is rocked out of engagement with the gears 451 by a semi-circular shaft 455 which is rocked by an arm 456 pivoted to a link 457 (see Fig. 2). The lowermost arm 456 has an extension 458 which is pivoted to one end of a link 461 whose other end is connected to an arm 462 fixed to shaft 463. The shaft 463 (see Fig. 8) extends to the interior of the machine and carries an arm 464 having a cam roller 465 cooperating with a cam 466 on shaft 228. This shaft, it will be recalled is driven from the list shaft and rotates each machine cycle, thereby, through the linkage just described, rocking the shafts 455 (Fig. 22) to release the total printing wheels.

Each accumulator is provided with a slug 467 150

(Fig. 24) having type representing the number of the counter. This slug is located opposite the total printing line so that whenever a total is struck from the counter the counter number as well as the total standing thereon will be printed.

The total printing carriage is indicated generally at 470 (Figs. 1a, 2 and 3). Two vertical feed screws 471 cooperate with threaded members on the carriage 470 and are rotated first in one direction to feed the carriage upwardly past the several horizontal rows of accumulators and then in the opposite direction to return the carriage to home position. As the carriage passes each horizontal row of accumulators suitable printing mechanism, to be hereinafter described, operates to print the total from each accumulator in the row.

Total taking may be initiated (see Figs. 43 and 43a) by shifting total lever 61a permitting it to be latched by member 61b and to close contacts 610 and 620 and incidentally open normally closed contacts 605 and 607. The shifting of total lever 61a also shifts link 82 as previously explained so that on energization of the clutch control magnet 68 the total clutch and the listing clutch will operate through their respective control levers 85 and 70. On each total taking operation totals are taken from all accumulators and it is necessary to maintain the machine in operation for several machine cycles for this purpose. After lever 61a has been shifted the machine may be started by momentarily depressing start key 57, establishing a circuit from source S through wire 614, start key contacts 57, contacts 620, which shunt the selecting key locking contacts 289 and 290, and clutch control magnet 68 through common return 254 to the other side of source S. Immediately after the operation starts, contacts 615 close, shunting start key contacts 57 and contacts 620, and these contacts hold the machine in operation, as will be explained later, until the necessary total taking cycles have been effected, after which they automatically open to stop the machine.

At the end of total taking the contacts 617 close momentarily, as will also be explained later, to energize total release magnet 91 which trips out latch 61b for the total lever and allows the latter to return to normal home position, whereupon the machine is conditioned for further accumulating.

It will be recalled that during total taking the total print carriage 470 feeds first upwardly past the total printing wheels to receive impressions and then downwardly to home position.

During the total taking operation the total shaft 74 rotates and drives the several mechanisms which are necessary to this operation. The feed screws 471 for the total printing carriage 470 (Figs. 2 and 5) are driven through bevel gears 472 from shaft 95 which is driven from total shaft 74 through reversing mechanism most clearly shown in Figs. 38 and 39. Total shaft 74 has two gears 475 and 476 freely mounted thereon each provided with a clutch member 477 and 478 respectively. A common cooperating clutch member 479 is splined to shaft 74 to rotate therewith and may be shifted into clutching engagement with either clutch member 477 or clutch member 478. The shifting mechanism consists of a pivoted lever 483 whose end rides in an annular groove in clutch member 479. This lever is connected through link 484 to a pivoted lever 485 whose lower end is provided with a double cam surface 486 and which has an extension midway

its length also provided with a double cam surface 487.

At the beginning of the total operation the clutch member 479 is in engagement with clutch member 477 driving gear wheel 475 which through gear wheel 488 fixed to shaft 95 drives the latter in a direction to feed the total printing carriage upwardly. The shaft 95 is provided with screw threads at 491 on which is threaded a block 492 having two downward projections 493 and 494 and an upward projection 495 having a hole through which extends a fixed rod 496 to prevent the block 492 from turning. As the shaft 95 rotates in a forward direction the block 492 feeds to the right and as it approaches the limit of its travel the upward extension 495 compresses a spring 497 tending to turn bell crank 501 clockwise. Incidentally lower extension 493 encounters a pin 502 on lever 485 and forces this lever slightly to the right.

When the lever reaches a location at which the middle of the double cam surface 487 passes the high point of a cam surface 503 on the end of bell crank 501 the action of spring 497 causes the cam surfaces 487 and 503 to snap lever 485 to the right shifting lever 483 which moves clutch member 479 out of engagement with clutch member 477 and into engagement with clutch member 478. The snapping of lever 485 to the right is assisted by bell crank 505 urged clockwise by a spring 506 and having a double cam surface 507 cooperating with cam surfaces 486.

The gear 476 is now driven by shaft 74 and through gear 508 drives a counter shaft 509 which carries a gear 510 meshing with a gear 511 on shaft 95. Owing to the presence of an extra gear 110 in this train the shaft 95 is now driven in reverse direction and serves to lower the total printing carriage to home position.

Meanwhile the block 492 feeds to the left and reaches its extreme left hand position just as the total carriage reaches home position. At this time lower extension 494 on block 492 encounters pin 502 on lever 485 and moves the latter slightly to the left. Then through a spring 512 and bell crank 513, entirely similar to spring 497 and bell crank 501, the lever 485 is again snapped to the left engaging clutch member 479 with clutch member 477 in readiness for a subsequent total printing operation.

The total printing carriage is shown generally in Figs. 1a, 2 and 3 and is detailed in Figs. 31 to 37 inclusive. The carriage consists of two side plates 530 and 531 joined by cross rods 532 and 533. Integral with each side plate are formed two spaced cylindrical enlargements 534 and 535 tapped to make screw threaded engagement with the vertical feeding screws 471. When these screws turn in one direction the carriage feeds upward past the total printing wheels 450 and when the screws turn in reverse direction the carriage feeds downwardly to home position. The entire total printing mechanism is swingingly suspended from the side plates of the carriage. An arm 536 pivoted to side plate 530 and an arm 537 pivoted to side plate 531 form the swinging supports for the cradle carrying the printing mechanism. The power for driving the several operating parts, such as paper feed, ribbon feed and hammer mechanism, is obtained from a spiral gear 540 splined to feed screw 471 and held between tapped enlargements 535 on side plate 531. This gear meshes with another spiral gear 541 which drives shaft 542 through gear train 543. The shaft 542 furnishes power for the unit.

A frame consisting principally of casting 545

150

forms the main supporting structure for the printing mechanism and is pivoted on shaft 542. Side plates 546 and 547 integral with this casting rotatably support the printing roll 548. The roll is held in place by gravity and its pivoted supporting arms 551 normally rest against lugs 552 on side plates 546 and 547. The paper 553 is led from roll 548 over rod 554 and guide 555 to the vicinity of total printing wheels 450 and 10 through feed rollers 556 and 557. The roll 556 is journaled in fixed position in the side plates of casting 545 but roll 557 has its shaft 561 journaled in arms 562 pivoted to side plates 546 and 547 and springs 563 yieldably force this roll into 15 engagement with roll 557.

The printing hammers 564 are pivoted on shaft 565 supported at each end on notched supports 566 (Fig. 34). The shaft is removably held in the notches by manually operated latches 567 so 20 that it may be removed for repair or replacement of the hammers.

The printing ribbon 568 is shown as a continuous band and is guided between the paper 553 and printing wheels 450. Suitable rods 571 25 on the casting 545 serve to guide the ribbon at other portions of its path and a tension roller 572 mounted on spring actuated bell crank 573 operates in a fold of the ribbon to keep it properly taut.

30 Total printing, as previously stated, occurs as the carriage in feeding upwardly on feed screws 471 comes opposite each row of total printing wheels. The cradle being pivoted on arms 536 and 537 carries most of its weight on the side 35 of the pivot opposite the printing wheels and so tends to swing to bring the printing ribbon into contact with the total wheels. This is normally prevented by a lug 575 (Fig. 37) cooperating with a cam 576 on shaft 542. When the carriage is 40 between the several horizontal rows of wheels the concentric portion of this cam through lug 575 holds the cradle with the printing ribbon slightly spaced from the wheels as in Figs. 33 and 36. When the carriage arrives opposite each row of 45 printing wheels a notch in the cam 576 is presented to the lug 575 and the cradle swings slightly, through gravity, to bring the ribbon almost into contact with the printing wheels as shown in Fig. 37.

50 At this time also the hammers 564 are operated to force the paper and printing ribbon against each row of type wheels. Each hammer has a notch 577 into which extends a common plate 578 fixed to shaft 581. The shaft is urged by a 55 spring 582 (Fig. 36) in clockwise direction to bring hammers 564 almost into engagement with the paper 553. As shaft 542 rotates in response to the upward movement of the printing carriage a notched disk 583 (see Fig. 34) fast to the shaft 60 cooperates with a pawl 584 pivoted on cam 585 loose on the shaft and causes the cam to rotate. The cam gradually rocks an arm 586 fixed to shaft 581 and tensions spring 582 thus causing hammers 564 to be drawn back. Just as 65 the carriage reaches each row of total print wheels the arm 586 drops off the high point of cam 585 and spring 582 moves shaft 581 quickly clockwise, whereupon plate 578 causes each hammer to drive the paper and printing ribbon smartly against the printing wheels to take an 70 impression.

75 During the reverse rotation of shaft 542 on downward movement of the printing carriage the pawl 584 clicks idly over the notch in disk 583 and consequently the cam 585 does not ro-

tate thus suppressing operation of the hammers.

After each printing stroke the paper and printing ribbon are spaced. The feed roll 557 (Fig. 34) carries a ratchet wheel 587. A cam 588 fixed to cam 585 to rotate therewith cooperates with a roll 591 on pivoted lever 592, a suitable spring holding the roll against the cam. At its opposite end the lever 592 carries a pawl 593 spring pressed into engagement with the ratchet wheel 587. During rotation the cam 588 rocks the lever 592 causing the pawl 593 to click over the ratchet teeth in succession and feed roll 557 and consequently paper 553 move the space of one ratchet tooth after each total printing operation.

The ribbon feed is effected from shaft 542 80 through bevelled gears 595 and 596, the latter driving a suitable spur gear train 597 for operating feed rolls 598 for the ribbon (Figs. 32a and 37).

The interior supporting structure for the total printing mechanism, consisting of the casting 545 may be swung back if desired to permit inspection and repair of the parts carried by it. This structure, it will be recalled, is pivoted on shaft 542 and as the greater portion of the weight 95 lies between the shaft 542 and the printing wheels, gravity holds the structure in its operative position. The structure may be swung around its pivot 542, however, until extension 601 on casting 542 strikes rod 602 thus exposing 100 the operating mechanisms.

Accumulator reset

Each horizontal row of accumulators is reset or zeroized after its total is printed. Zeroizing 110 is effected by displacing the accumulator racks 146 (Fig. 22) to their limiting position, then meshing the accumulating wheels with them and returning the racks, rolling the wheels backward, until their transfer projections 205 strike 115 the transfer hooks 204. This stops the wheels and racks with the wheels in zero position and the springs 701 stretch to permit the rack operating mechanism to complete its restoring movement. At the end of the cycle the wheels are 120 demeshed from the rack and remain in zero position while the springs 701 draw the racks back to their normal position.

This reset operation may be more clearly understood from Figs. 6, 13, 19 and 22. In Fig. 125 13 when total lever 61a is shifted it also shifts a link 702 and thereby rocks shaft 703. This shaft (see also Fig. 19) carries a bail 704 which rocks the zero latches 111 for the differential mechanisms out of the path of the latter and 130 permits them to operate, it being borne in mind that the listing shaft as well as the total shaft rotates during totaling. The racks 146 (Fig. 22) are thus displaced to the extent of their movement to the left. The accumulator control 135 magnets 175 are then energized to rock the accumulator frames and bring their wheels into mesh with the racks. The operating bars 145 and arms 148 restore to normal position with an uninterrupted motion but the wheels and racks 140 stop when the wheels reach zero position and transfer extensions 205 encounter the flat reverse side of transfer hooks 204. The pin 147 at this time slides in its coacting slot in the rack and the spring 701 stretches to permit the restoration of arms 148 and operating bars 145.

During this operation the transfer mechanism is locked as it will be recalled that some of the transfer racks may have been displaced from previous carrying operations and to restore them 150

at this time would result in undesired entries into the accumulator wheels. The cam 227 (Fig. 8) rocks arm 225 and shaft 224 as usual but the arm 225 is latched by latch 710 which 5 is released for this purpose by cam 711 on total shaft 74. The latch 710 retains arm 225 until the end of the cycle when the hump on cam 711 again rocks it to inoperative position. The shaft 224 being thus held rocked (see Figs. 2 and 22) 10 moves and holds the shaft 216 with plate 217 above members 209 on the transfer racks so that there can be no operation of the latter during total taking.

At the end of the cycle the accumulator magnets 175 are deenergized and the accumulator frames rock back into unmeshed position retaining the wheels at zero. On the unmeshing of the wheels, springs 701 retract racks 146 and the 15 accumulator is completely restored.

20 The control of the magnets 175 during total taking and reset will now be explained in connection with Figs. 2, 5, 26 to 30 and 43 and 43a. As the printing carriage 470 feeds upwardly and takes an impression from each horizontal row 25 of accumulators, the accumulators of each row are zeroized shortly after their impression has been taken and before the impression is taken from the next higher row. The shaft 95 (Fig. 2) which as previously explained rotates first in 30 one direction to feed the total printing carriage upwardly and then in the reverse direction to restore the carriage, also drives a shaft 715 geared to a shaft 716. This latter shaft also rotates first in one direction and then in the other in synchronization with the movement of the total print carriage.

35 The shaft 716 (Fig. 26) operates a contact mechanism, which will hereinafter be referred to as the total timer, whose principal function 40 is to time the energization of the accumulator selecting magnets 175 so that the accumulators of each row will be reset at the proper times. The shaft 716 is screw threaded and carries an interiorly screw threaded block 717 having extensions 718 and 719 engaging a shaft 720. The 45 block 717 thus feeds along the shaft 716 as the latter rotates. The shaft 720 is rotated by gears 723 and a sleeve 721 is splined to it between extensions 718 and 719. The sleeve carries a spiral 50 flange 722 which rocks bell cranks 724 in succession and closes associated contacts T-1, T-2, T-3 etc. which latter control circuits for energizing the accumulator magnets 175. Associated with each contact pair T-1, T-2 etc. is another pair T-11, T-21 etc. whose function will 55 be explained later.

At the right hand end of shaft 720 is a special contact GT-1 which is attached by an insulating plate to its neighboring contact T-10 and 60 closes with it.

An extension 725 on the lower part of block 717 controls contacts 615 which, as previously explained, maintain the machine in operation during the several total taking cycles and stop 65 it on the completion of these cycles. These contacts are urged into engagement by the resiliency of one of them but may be held apart by a lever 726 operated by rod 727. The rod extends through a hole in extension 725 and has a head formed 70 on its end so that as long as block 717 remains in its home position the lever 726 holds contacts 615 open. When the block 717 leaves home position contacts 615 close and remain closed until the block again reaches home position at the end 75 of total taking.

Contacts 617 which control the total trip magnet to cause release of the total lever at the end of totaling are also controlled by the block 717. Contacts 617 are normally open but may be closed by a lever 731 which is connected to lever 732 by rod 733. A spring pressed pawl 734 on block 717 snaps over lever 732 when the block starts its movement to the right but on its return movement rocks the lever to close contacts 617 momentarily to energize the total trip magnet 80 at the end of totaling.

85 It is desirable that the resetting or zeroizing circuits be energized only on the movement of block 717 to the right as its leftward movement is merely a restoring one. This is done by a series of cam contacts designated by TR followed by a numeral whose operating cams are mounted on a shaft 735. The shaft 735 is an alignment with shaft 720 and connected to it by a one way drive device so that it operates when shaft 720 rotates 90 in one direction but not when shaft 720 rotates in reverse direction. The one way drive (Figs. 28 and 30) consists of a disk 736 fixed to shaft 735 and carrying a pivoted spring pressed pawl 736'. The pawl coacts with a disk 737 having a single 100 tooth which engages pawl 736' to rotate shaft 735 in one direction but over which the pawl clicks idly on rotation in the other direction. The contacts TR-1 to TR-14 are normally open and are closed during each active total taking cycle 105 by levers 738 rocked by cams 739 on shaft 735.

110 The accumulator selecting magnets 175 are not energized directly from their corresponding cam contacts T-11, T-21 etc. but by means of relays 800, whose mechanical structure is shown in Fig. 110 9. One relay is provided for each horizontal row of accumulator magnets and when its coil is energized closes contacts R-11, R-21, R-31 and RA for each accumulator and opens a normally closed contact R-1. The contacts tend to remain 115 in normal position by their own resiliency and when coil 800 is energized it attracts its armature and rocks a member 801 against the action of spring 803 thereby shifting a notched bar 802 to operate the contacts.

120 The sequential operation of the accumulator magnets 175 for zeroizing may be understood from Figs. 43 and 43a. The lower row comprising magnets for accumulators K, 9, 19, 29 and 39 are energized first on closing of cam contacts T-1 and 125 T-11. Contacts T-1 control the secondary accumulator K through the following circuit: from source S through wire 614, contacts TR-4 and wire 741 to cam contacts T-1, thence through magnet of accumulator K and contacts TR-5 130 back to the source S through common return 254. Contacts T-11 control the primary accumulators 9, 19, 29 and 39 through a relay 800. This relay 135 closes its contacts R-9, R-19, R-29 and R-39 and completes the resetting circuits for these accumulators. The circuit for accumulator 9 extends from source S through cam contacts L-1, wires 246 and 269 to relay contacts R-9 and accumulator magnet and through wire 255 and contacts 236 to common return wires 253 and 254 140 to the other side of source S. The circuits for the other magnets are similar.

145 During successive total taking cycles cam contacts T-2, T-3, T-4 etc. close in order to zeroize the successive horizontal rows of accumulators. The circuits are entirely similar to those just traced with the exception of that for the grand total GT in the topmost row. This is controlled directly from cam contacts GT-1 shown to the extreme right of shaft 720 in Fig. 26. 150

It will be recalled that cam contacts T-1, T-2, T-3, etc. close when the printing carriage feeds down as well as when it feeds up but each zeroizing circuit contains at least one of the TR cam contacts which close only during upward feed of the carriage.

General operation

The machine is first plugged (see Fig. 3) to connect any desired secondary accumulators, A to K, with any desired primary accumulators so that any entry made in a primary accumulator will likewise be made in the selected secondary accumulator or accumulators. Amounts may then be set up by manipulating the amount keys 50 and the primary accumulators selected by depressing the proper counter selecting keys 51 and 52. Until an accumulator has been selected the operation of the machine is prevented. The machine may be started by depressing the operating key 57 which causes it to perform a single entering cycle, entering the amount into the selected primary and secondary accumulators. Also each entry will be entered in the grand total accumulator which needs no selection. Successive amounts may be entered in this manner and if desired an amount may be repeated without additional set up by operation of the repeat mechanism 60. Each entered item will be listed on the item strip as illustrated in Fig. 42.

The accumulators are arranged in vertical and horizontal rows (Figs. 1, 1a and 3) so that their total printing wheels are exposed in a vertical plane. Total taking may be initiated by manipulating the total print mechanism 61 and depressing the start key 57. This causes the machine to operate and the total print carriage 470, which carries the total strip, to feed upwardly past the horizontal rows of accumulators. As it arrives opposite each row a printed impression of the total of each accumulator in the row is made on the total strip (illustrated in Fig. 41) and the accumulators are automatically zeroized. After all totals have been printed the total print carriage feeds back to home position and the printed portion of the total strip may be detached. This whole total printing operation is automatic after it is once initiated.

The invention has now been explained in what is at present believed to be its preferred embodiment but it will be obvious that many changes in the mechanism and its mode of operation will readily suggest themselves to those skilled in the art without departing from the scope of the invention. The invention is to be limited only as indicated by the following claims.

What is claimed is:

1. In an accounting machine a plurality of primary accumulators, manipulative means for controlling the entry of data thereon, selective mechanism for selectively associating any primary accumulator with the manipulative means for data entry, a plurality of secondary accumulators electromagnetic operating means therefor and circuits completed by the primary accumulators on selection for data entry to operate said electromagnets to associate the plurality of secondary accumulators with the manipulative means to receive the data entry.
2. In an accounting machine a plurality of primary accumulators, a plurality of secondary accumulators, manipulative means for controlling the entry of data thereon, selective mechanism for selectively associating any primary accumulator with the manipulative means for data

entry, selective means operated by each primary accumulator on selection thereof to operatively associate a secondary accumulator with the manipulative means to receive the same data entry and means for selectively associating any secondary accumulator with the selective means operated by any primary accumulator.

3. In an accounting machine a plurality of groups of accumulators, manipulative means for controlling the entry of data thereon, selective means including electric circuit connections for operatively associating any desired accumulator of one group with the manipulative means for receiving data entries and means including further circuit connections operated by an accumulator so selected for operatively associating any accumulator of another group with the manipulative means to receive the same data entries.

4. In an accounting machine, a plurality of primary accumulators and a plurality of secondary accumulators each having a plurality of denominational order elements, a displaceable rack for each element to operate the same, a group of digit keys for controlling the displacement of all racks of a denominational order, electromagnetic means associated with each accumulator for operatively connecting it to its racks, manipulative means for selectively controlling the electromagnetic means of the primary accumulators to effect selection of any primary accumulator for control by the digit keys and means operated by the primary accumulators for controlling the electromagnetic means of the secondary accumulators.

5. In an accounting machine, a plurality of accumulators having several denominational orders and operating mechanism for the same, selective mechanism for selectively and concurrently connecting the several orders of an accumulator with the operating mechanism, said selective mechanism comprising a plurality of groups of selecting members each member controlling devices certain of which tend to select a plurality of accumulators and interlocking means between the several groups for limiting the selection to a single accumulator when selecting members of several groups are operated.

6. In an accounting machine, a plurality of accumulators having several denominational orders and operating mechanism for the same, selective mechanism for selectively connecting the several denominational orders of the accumulators with the operating mechanism, said selecting mechanism comprising a plurality of groups of selecting members, certain members of each group controlling devices tending to select a plurality of accumulators of which one only is common to more than one group of selecting members and interlocking devices controlled by each member for disabling all members of other groups except that which controls the accumulator common to all groups operated.

7. In an accounting machine, a plurality of accumulators having several denominational orders and operating mechanism for the same, an electromagnet for each accumulator to operatively and concurrently connect all its orders to the operating mechanism and a controlling circuit for each electromagnet consisting of a plurality of branches each branch including a plurality of circuit closers disposed in groups of which one group closes a break in a number of circuit branches and of which another group closes a break in one only of the number of branches closed by the first.

8. In an accounting machine, a plurality of accumulators, each having total recording devices, a total recording carriage carrying record receiving material, means for moving the carriage past a number of the total recording devices in succession and means for effecting recording by the total recording devices on the record receiving material as the carriage arrives opposite the total recording devices of each accumulator. 80
10. 9. In an accounting machine, a plurality of accumulators each having total recording devices, a total recording carriage carrying record receiving material, means for reciprocating the carriage first in one direction past a number of the total recording devices and then in a reverse direction, total taking means for effecting recording by the total recording devices on the record receiving material as the carriage arrives opposite the total recording devices of each accumulator on carriage movement in one direction and means for preventing operation of the total taking means on movement of the carriage in the other direction. 85
15. 10. In an accounting machine, a plurality of accumulators, each having total recording devices, a total recording carriage carrying record receiving material, means for moving the carriage past each total recording device in succession and means for zeroizing each total recording device after its total has been recorded and before the carriage arrives opposite the next total recording device in order. 90
20. 11. In an accounting machine, a plurality of accumulators, each having total recording devices, a total recording carriage having provisions for supporting record receiving material, means for reciprocating the carriage first in one direction past the total taking devices and then in reverse direction, electromagnetic means for operating the total recording devices of each accumulator, a circuit for each electromagnetic means, means for closing the circuits successively as the carriage arrives opposite the respective total recording devices on movement in one direction and means for preventing closure of the circuits on movement of the carriage in the reverse direction. 95
25. 12. In an accounting machine, a plurality of accumulators, record taking mechanism associated therewith including a carriage having provisions for supporting recording receiving material and movable past the several accumulators first in one direction and then in reverse direction, electrically operated mechanism for each accumulator to operate the same on a recording operation, a plurality of circuits for controlling said electrically operated mechanisms and timing means for closing said circuits successively as the carriage arrives opposite the several accumulators on movement in one direction only, said timing means comprising a pair of shafts each controlling contact devices in the circuits and a two way drive for one shaft and a one way drive for the other operated from a common driving device. 100
30. 13. In an accounting machine a plurality of accumulators, a plurality of keys for effecting operation of the accumulators, and electromagnetic devices controlled by the keys, circuits for the electromagnetic devices, a plurality of movable contact elements in said circuits one for each key with means for imparting a limited movement to the same whereby said elements are moved in the paths of their associated keys when the latter are in depressed position and contact elements mounted on said keys for coacting with said first named contact elements. 105
35. 14. In an accounting machine including listing mechanism and totaling mechanism, a driving device and separate clutches for connecting the listing and totaling mechanisms thereto, an operating member for effecting engagement of the listing clutch and means controlled from the totaling mechanism for placing the total clutch 110 also under control of said operating member. 110
40. 15. In an accounting machine including listing mechanism and totaling mechanism, a driving device and separate clutches for connecting the listing and totaling mechanisms thereto, a movable control member for effecting engagement of the listing clutch, a movable control member for effecting engagement of the totaling clutch and means for moving said total clutch control member into the path of the listing clutch 115 control member to cause engagement of both clutches on a totaling operation. 120
